UNITED STATES PATENT OFFICE.

CHARLES OTTO SCHNEIDER, OF WIMBLEDON, LONDON, ENGLAND.

TROUSERS-STRETCHER.

1,061,329.

Specification of Letters Patent.

Patented May 13, 1913.

Application filed August 24, 1912. Serial No. 716,822.

To all whom it may concern:

Be it known that I, CHARLES OTTO SCHNEIDER, a subject of the Emperor of Germany, residing in Wimbledon, London, 5 England, have invented certain new and useful Improvements in Trouzers-Stretchers, of which the following is a specification.

This invention relates to an improved trousers stretcher and it relates to devices 10 of the kind comprising two clamp members for engaging the ends of the garment which are held apart to effect the stretching operation by means of a rigid jointed member.

The present invention has for its object 15 to provide an efficient device for the purpose specified which, while being cheap, shall be both light in weight and capable when not in use of being reduced to a much smaller compass than devices of the type as 20 usually constructed, thereby permitting it to be readily packed for transport. A device according to the present invention moreover is of such small bulk that even when in use with the garment therein, it may be readily 25 packed for transport.

A device according to this invention comprises a pair of metal clamps one for engaging the upper end of the garment, and the other, which is shorter, for engaging the 30 lower end of the said garment. The clamps comprise strips of thin metal corrugated, ribbed or embossed to add to the rigidity thereof, and the strips are pivotally connected at one end by means of a resilient member 35 formed of thin sheet metal which is at one end attached to one of the members of the clamp, and at the other pivotally connected to the other member of said clamp. The opposite ends of the members of the 40 clamp are provided respectively with a second resilient member and a clip or fastening engaging the end of said resilient member. The clamps are held apart to effect the stretching operation by means of a rod 45 formed in two parts and connected by means of a sleeve and ball and socket joint. The outer ends of the rod are slotted and a projection is formed upon one of the members of each clip which is engaged by the slotted 50 ends of the jointed rod.

In order that the invention may be the better understood drawings are appended in which:—

Figure 1, is a side view with the parts in 55 the position ready for use. Fig. 2, is an enlarged section on line A A Fig. 1. Fig. 3,

is a side view of one end of one of the clamps. Fig. 4, is a similar view of the other end. Fig. 5, is a plan of the parts shown in Fig. 3. Fig. 6, is a plan of the 60 parts shown in Fig. 4. Fig. 7, is a front end view of one of the clamps. Fig. 8, is a plan of the back portion of one end of the clamps.

Referring to the accompanying drawings 65 *a a¹* indicate strips of thin metal ribbed longitudinally at *a²* for strengthening purposes. The strips form clamps of which one is provided for the upper end of the garment and another of somewhat less length 70 for the lower end of said garment. The strips *a a¹* are pivotally connected at one end by means of the resilient member *b* riveted or otherwise secured to the end of strip *a* and having its outer end turned or bent to form 75 an eye *b¹* through which passes a pin *b²* engaging similar eyes *b³* upon the end of strip *a¹*. One or both of the inner faces of the strips *a a¹* is or are provided with a fabric or other suitable cover *c* designed to prevent 80 any damage to the garment and at the same time increase the holding power of the clamp by preventing the slipping of the garment between the members of the clamp. The opposite end of the member *a* has secured 85 to it a second resilient member *d* the outer end of which is bent or shaped as shown so that there is formed adjacent the free end of said member *a* a recess *e*. The member *a¹* has formed upon its opposite end 90 eyes *f* which support a clip *f¹* designed to hold the members of the clamp together and which clip is brought over the end of the resilient member *d* and engages the aforesaid recess *e* in the end of said member as 95 clearly shown in Fig. 3. To facilitate the manipulation of the clips I prefer to provide it with an extension or finger piece *f²*. By employing the resilient members at each 100 end of the clamp it is possible to secure an even pressure throughout the length of the clamps and at the same time the clamp will automatically adjust itself to different thicknesses of material at the same time exerting 105 an even pressure as aforesaid.

Formed upon one of the members of the clamp are projections which are conveniently formed by indenting the metal from the inside of the member so that there is formed, as clearly shown in Fig. 2, a projection *g*. The projections *g* are formed on each clamp and are designed to be en- 110

gaged by the slotted ends of the rod *h* by means of which the clamps are held apart to effect the stretching operation as shown in Fig. 1. The rod *h* is formed in two parts connected in any suitable manner, in the present instance by means of the ball and socket joint indicated generally by *i* Fig. 1, a sleeve *i*¹ serving to hold the parts of the rod in alinement.

10 Claims:

10 A trousers stretcher comprising a member for engaging one end of the trousers, a member for engaging the other end of said trousers, said members being each formed in 15 two parts of thin sheet material, a resilient member connected to one of said parts and pivotally connected to the other part, a second resilient member attached to the oppo-

site end of one of the parts, and a clip upon the end of the other part engaging the end 20 of said resilient member, a rod formed in two parts, a ball upon the inner end of one part of the rod, a socket upon the inner end of the other part of the rod, a sleeve for retaining the parts of the rod in alinement, 25 a slot in each end of the rod, a projection upon each of the trousers engaging members whereby said slots may engage said members to enable the rod to hold them apart.

Signed in the presence of the two under- 30 signed witnesses.

CHARLES OTTO SCHNEIDER.
